DISTRIBUTING MECHANISM FOR ELECTRICAL IGNITION SYSTEMS.

1,226,817.

Specification of Letters Patent.

Patented May 22, 1917.

Application filed February 15, 1916. Serial No. 78,489.

To all whom it may concern:

Be it known that I, WOLFGANG E. SCHWARZMANN, a citizen of the United States, residing at and whose post-office address is No. 51 Belleclaire avenue, Long Meadow, Springfield, county of Hampden, State of Massachusetts, have invented certain new and useful Improvements in Distributing Mechanism for Electrical Ignition Systems; and I do hereby declare the following to be a full, clear, and exact description of the invention, such as will enable others skilled in the art to which it appertains to make and use the same.

Prior forms of distributers for magnetos for internal combustion engines having eight or more cylinders have their contact segments arranged in two circular series, so that without exceeding practicable dimensions, the segments may have sufficient peripheral extent to provide for the required timing range and at the same time have sufficient separation to prevent simultaneous engagement by the distributing brush. In one form of this construction, sparks are produced simultaneously at two spark plugs in series at each period of ignition, thus requiring a considerably higher ignition voltage, and also interfering with the best performance of engines having eight or more cylinders. Heretofore, in providing distributing mechanism in which the contact segments are arranged in two series as before, but in which a spark is produced at a single spark plug instead of at two spark plugs in series, the terminals of the secondary winding of the magneto are insulated from the primary winding, so that in this case, as well as in the case of two spark plugs in series, the use of the autotransformer connection between the primary and secondary windings is not shown.

In accordance with the present invention in application to an engine of many cylinders, the contact segments of a main distributer are arranged in two series, and a spark is produced at a single spark plug at each period of ignition, but the primary and secondary windings of the magneto may have an autotransformer connection. This is accomplished by so arranging the main distributer that at each period of ignition, one distributing brush engages a segment of

its series, while the other distributing brush sets between adjacent segments of its series, 55 an intermediate distributer being used to complete the electrical connection from the insulated terminal of the secondary winding to the brush which at that time engages a segment. In case the armature winding is 60 grounded, the ignition current produced at each period of ignition flows from the insulated terminal of the winding, through the intermediate distributer to the insulated electrode of the spark plug connected to the 65 contact segment of the main distributer then engaged by a brush, and thence by way of the frame to the grounded terminal of the winding. In a four-cycle internal combustion engine, this main distributer is driven 70 at half crank shaft speed, and preferably the contact segments are stationary and opposite each other in two circular series, while the brushes are rotatable and are relatively advanced by half the angular separation of 75 adjacent segments of a series. This relation of segments and brushes, together with the selection of the speed of rotation relatively to that of the crank shaft of the engine, constitutes a form of main distributer that can 80 also be used in ignition systems embodying magnetos having both terminals of its secondary winding insulated from the primary winding, and therefore the appended claims 85 are intended to cover this feature separately 85 as well as in combination with other features of the distributing mechanism specifically disclosed hereinafter.

The accompanying drawings show the preferred form of the invention in application, 90 as an example, to a magneto generating four ignition voltages per rotation, and to a four-cycle internal combustion engine having twelve cylinders. In the drawings,

Figure 1 is a central vertical section taken 95 longitudinally of the magneto; Fig. 2 is a section on line 2—2 of Fig. 1; and Fig. 3 is a wiring diagram.

The construction of the magneto proper and the mechanical interrupter is like that 100 disclosed in the copending application of Otto Heins and Charles M. Wild, Serial No. 68841, filed December 27, 1915. The rotor of the magneto is the armature 1 which is of the ordinary shuttle type having high and low 105 tension windings and which is mounted for

rotation in the bearings 2. The stationary field member comprises two permanent magnets 4 and 5 of horse-shoe form arranged side by side along the axis of the armature. 5 The magnet 4 is wider than the magnet 5 and each has two diametrically-disposed pole shoes at right angles to the pole shoes of the other magnet. The arrangement is such that one axial portion of the polar 10 projections of the armature bridges the spaces between the pole shoes of the magnet 4 twice in each rotation, whereas the remaining axial portion of the polar projections of the armature bridges the spaces between the pole shoes of the magnet 5 twice 15 in the same rotation, these periods occurring at 90° intervals in substantial coincidence with the period of interruption of the primary winding by the mechanical interrupter 6. In this way four substantially like ignition 20 voltages are generated in the secondary winding at 90° intervals in each rotation of the armature.

The high tension or insulated terminal of the secondary winding is connected to both axially-offset segments 7 and 7' which are embedded in the rings 8 of insulating material at diametrically opposite places, each segment having a peripheral extent of approximately 90°. The segments 7 and 7' are carried by the armature for rotation therewith, and successively engage the two sets of brushes 9, 9' and 10, 10', which sets are disposed at 90° to each other and are 30 insulated from each other and from the ground. The brushes 9, 9' are electrically connected together and to the brush 12, while the brushes 10, 10' are electrically connected together and to the brush 12', the 35 two brushes 12 and 12' being arranged to be driven through a one to three speed reducing gearing formed by the pinion 13 on the armature and the gear 14 on the rotating shaft 15. The stationary contact segments 40 16, 16' are disposed opposite each other and in insulating material in two circular series, and the brushes 12 and 12' are so positioned that while one engages a segment of its series, the other one sets between two adjacent 45 segments of its series, that is, in the construction shown, the two brushes 12 and 12' are relatively advanced by an angle of 30°. The contact segments 16, 16' are in the usual way connected to the insulated electrodes of 50 the individual spark plugs, the other electrodes of the spark plugs being grounded on the engine frame. The segments 7, 7' and the coöperating brushes 9, 9', 10, 10' form an intermediate distributor between 55 the generating winding 18 and the main distributor and are adapted to periodically interrupt the circuit therebetween but at each period of ignition to conduct the ignition current from the winding to a single one of 60 the contact segments 16 or 16' of the main 65

distributer by completing the circuit to a single one of the brushes 12 or 12' thereof.

In this ignition system for a twelve-cylinder four-cycle engine, the shaft of the armature is driven by the engine at one and one-half times crank shaft speed, and the rotatable brushes 12 and 12' are therefore driven at one-half times crank shaft speed, so that for each 60° of rotation of the crank shaft, the magneto rotates through 90° and generates one ignition voltage, while each main distributor brush 12 or 12' moves through one-half the distance between adjacent segments of the respective series. 70

Referring now to Fig. 3, it will be observed that the primary winding 17 is grounded on one side, and is connected on the other side to one terminal of the secondary winding 18 and also to the insulated element 19 of the mechanical interrupter 6, the two windings 17 and 18 having an autotransformer connection. The insulated element 19 engages the grounded element 20, except when the circuit of the primary winding is interrupted between those elements of the mechanical interrupter at each 90° of rotation of the armature. The insulated terminal of the high tension or secondary winding 18 is electrically connected to both contact segments 7 and 7' of the intermediate 80 distributor and the brushes are so positioned that the segments engage but one of them at a time. In the position shown in Fig. 3, the connection from the armature winding 17, 18 to the brush 12 is completed by the segment 7 and brush 9 of the intermediate distributor, whereas the electrical connection to the other distributor brush 12' is interrupted at the intermediate distributor by reason of the fact that both brushes 10 and 10' are at that time disengaged from both segments 7 and 7'. The ignition current produced in the secondary winding at this period of ignition therefore flows to the insulated electrode of the spark plug connected to the contact segment No. 1, and to no other spark plug. At the next period of ignition, which occurs when the armature has rotated through 90° from the position shown, the segment 7 is disengaged from both brushes 9 and 10, and the segment 7' is engaged with the brush 10'. The rotating brushes 12 and 12' will, in that part of the rotation, move through 30°, so that the brush 12 is then between the contact segments Nos. 1 and 3, while the brush 12' is in engagement with the contact segment No. 2, whereby the ignition current then produced in the secondary winding is conducted to the brush 12' while the brush 12 is disconnected. The spark therefore occurs at the spark plug connected to the segment No. 2, and at no other spark plug. When the armature has rotated through another 90°, the segment 7 is still disengaged from both 85 90 95 100 105 110 115 120 125 130

- brushes 9 and 10, but the segment 7' has moved out of engagement with the brush 10' and into engagement with the brush 9. The brush 12 is now in engagement with the contact segment No. 3 and the brush 12' has moved from its prior engagement with contact segment No. 2 into the space between it and segment No. 4. The ignition current then flows to the spark plug connected to contact segment No. 3, and to no other. After rotation of the armature of 90° from this last position, the segment 7' is disengaged with both brushes 9' and 10', while the segment 7 is now engaged with the brush 10. The ignition current produced at that period of ignition flows to the spark plug connected to the contact segment No. 4, which is then engaged by the brush 12', and flows to no other spark plug. This operation continues in such manner that the brush 12 conducts ignition current to a contact segment of one series 16, and then the other brush 12' conducts ignition current to a contact segment of the other series 16', the order being indicated by the numbers given to the contact segments in Fig. 3. Thus in each two rotations of the engine, the magneto produces twelve ignition currents which are conducted to the twelve spark plugs in turn.
- It will be apparent that in the specific arrangement shown herein, the magneto may be of any type in which four ignition currents are produced in each rotation of the armature. Also, in accordance with the broad ideas disclosed herein, the arrangement of the intermediate distributor and the main distributor may be modified, and may be used with magnetos producing more or less than four ignition currents per rotation, and with engines having more or less than twelve cylinders operating on the four-cycle or other principle.
- Having thus described my invention, what I claim is:
1. The combination with an internal combustion engine having spark plugs, and a magneto having an autotransformer winding, of distributing mechanism comprising a rotatable main distributor having contact segments electrically connected to individual spark plugs, and an intermediate distributor which is mounted on the rotor of the magneto and which, at each period of ignition, conducts the ignition current from said winding to a single one of said contact segments.
2. The combination with an internal combustion engine having grounded spark plugs, of a magneto having a grounded autotransformer winding, of distributing mechanism comprising a rotatable main distributor having contact segments electrically connected to the insulated electrodes of individual spark plugs, and an intermediate distributor which is mounted on the rotor of the magneto and which is
- and which, at each period of ignition, conducts ignition current from said winding to a single one of said contact segments.
3. The combination with an internal combustion engine having grounded spark plugs, and a magneto having a secondary winding with one terminal grounded and the other terminal insulated, of distributing mechanism comprising a rotatable main distributor having contact segments electrically connected to the insulated electrodes of individual spark plugs, and an intermediate distributor which is mounted on the rotor of the magneto and which, at each period of ignition, completes the electrical connection from the insulated terminal of said winding to a single one of said contact segments. 75
4. The combination with an internal combustion engine having spark plugs, and a magneto having an autotransformer winding, of distributing mechanism comprising a rotatable main distributor having contact segments electrically connected to individual spark plugs, and brushes coöperative with the segments, and also comprising an intermediate distributor which is mounted on the rotor of the magneto and which at each period of ignition, conducts the ignition current from said winding to a single one of said brushes. 80
5. The combination with an internal combustion engine having grounded spark plugs, and a magneto having a secondary winding with one terminal grounded and the other terminal insulated, of distributing mechanism comprising a rotatable main distributor having stationary contact segments electrically connected to the insulated electrodes of individual spark plugs, and rotatable brushes coöperative with the segments, and also comprising an intermediate distributor which is mounted on the rotor of the magneto and which, at each period of ignition, completes the electrical connection from the insulated terminal of said winding to a single one of said brushes. 85
6. The combination with an internal combustion engine having spark plugs, and a magneto having an autotransformer winding, of distributing mechanism comprising a rotatable main distributor having two series of contact segments electrically connected to individual spark plugs, and an intermediate distributor which is mounted on the rotor of the magneto and which, at each period of ignition, conducts the ignition current from said winding to a single one of said contact segments. 90
7. The combination with an internal combustion engine having spark plugs, and a magneto having a secondary winding with one terminal grounded and the other terminal insulated, of distributing mechanism comprising a rotatable main distributor having two series of contact segments electrically connected to individual spark plugs, and an intermediate distributor which is mounted on the rotor of the magneto and which, at each period of ignition, completes the electrical connection from the insulated terminal of said winding to a single one of said contact segments. 95
- 100

- cally connected to the insulated electrodes of individual spark plugs, and rotatable brushes coöperative with the segments, and also comprising an intermediate distributer 5 which is mounted on the rotor of the magneto and which, at each period of ignition, completes the electrical connection from the insulated terminal of said winding to a single one of said brushes.

10 8. The combination with an internal combustion engine having spark plugs, and a magneto having an autotransformer winding, of distributing mechanism comprising a rotatable main distributer having two 15 series of contact segments electrically connected to individual spark plugs, and rotatable brushes coöperative with the segments, and also comprising an intermediate distributer which is mounted on the rotor of the 20 magneto and, which, at each period of ignition, connects the insulated terminal of said winding to a single one of said brushes.

9. The combination with an internal combustion engine having spark plugs, and a magneto having a generating winding, of 25 distributing mechanism comprising a rotatable main distributer having two series of contact segments electrically connected to individual spark plugs, and two brushes 30 which alternately engage the contact segments of the individual series, and also comprising an intermediate distributer which is mounted on the rotor of the magneto and which, at each period of ignition, conducts 35 the ignition current from said winding to a single one of said brushes.

10. The combination with an internal combustion engine having grounded spark plugs, and a magneto having a secondary 40 winding with one terminal grounded and the other terminal insulated, of distributing mechanism comprising a rotatable main distributer having two series of contact segments electrically connected to the insulated 45 electrodes of individual spark plugs, and two brushes which alternately engage the contact segments of the individual series, and also comprising an intermediate distributer which is mounted on the rotor of the magneto and which, at each period of 50 ignition, completes the electrical connection from the insulated terminal of said winding to a single one of said brushes.

11. The combination with an internal combustion engine having grounded spark plugs, and a magneto having a secondary winding with one terminal grounded and the other terminal insulated, of distributing mechanism comprising a rotatable main distributer having two series of contact segments electrically connected to the insulated electrodes of individual spark plugs, and brushes coöperative with the contact segments, and also comprising a rotatable intermediate distributer having two axially- 55 offset segments connected to the insulated terminal of said winding, and two sets of brushes coöperative with the segments of the intermediate distributer and electrically connected to the individual brushes of the main distributer, the segments and brushes of the intermediate distributer being so constructed and arranged that, at each period of ignition, the ignition current is conducted to a single brush of the main distributer. 60

12. The combination with an internal combustion engine having grounded spark plugs, and a magneto having a secondary winding with one terminal grounded and the other terminal insulated, of distributing mechanism comprising a rotatable main distributer having two series of contact segments electrically connected to the insulated electrodes of individual spark plugs, and brushes coöperative with the contact segments, and also comprising a rotatable intermediate distributer having two axially-offset segments connected to the insulated terminal of the secondary winding, and two sets of brushes coöperative with the segments of the intermediate distributer and electrically connected to the individual brushes of the main distributer, the segments and brushes of the intermediate distributer being so constructed and arranged that, at each period of ignition, the electrical connection from the insulated terminal of the secondary winding is completed to a single one of the brushes of the main distributer. 65

13. The combination with a four-cycle internal combustion engine, and a magneto having a secondary winding, of distributing mechanism comprising a main distributer geared to run at half crank shaft speed and having two series of contact segments electrically connected to individual spark plugs, and also comprising an intermediate distributer which is electrically connected to the secondary winding and which, at each period of ignition, conducts the ignition current from said winding to a single one of said contact segments, said intermediate distributer being mounted on the rotor of the magneto. 70

14. The combination with a four-cycle internal combustion engine having spark plugs, and a magneto having a secondary winding, of distributing mechanism comprising a main distributer geared to run at half crank shaft speed and having two series of contact segments electrically connected to individual spark plugs, and also comprising an intermediate distributer which is mounted on the rotor of the magneto, and which, at each period of ignition, conducts the ignition current from said winding to a single one of said contact segments. 75

15. The combination with a four-cycle internal combustion engine having spark 80

- plugs, and a magneto having a secondary winding, of distributing mechanism comprising a main distributer geared to run at half crank shaft speed and having two series 5 of contact segments electrically connected to individual spark plugs, and brushes alternately engaging the contact segments of the individual series, and also comprising an intermediate distributer which is mounted on 10 the rotor of the magneto and which, at each period of ignition, conducts the ignition current from said winding to the brush then engaged with the contact segment.
16. The combination with a twelve-cylinder 15 internal combustion engine having grounded spark plugs, and a four-pole magneto having a secondary winding with one terminal grounded and the other terminal insulated, of distributing mechanism comprising a main distributer having contact 20 segments arranged in two series of six segments electrically connected to the insulated electrodes of individual spark plugs, and also comprising an intermediate distributer 25 which is mounted on the rotor of the magneto and which, at each period of ignition, completes the electrical connection from the insulated terminal of said winding to a single one of said contact segments.
- 30 17. The combination with a twelve-cylinder internal combustion engine having grounded spark plugs, and a four-pole magneto having an autotransformer winding with one terminal grounded and the other 35 terminal insulated, of distributing mechanism comprising a main distributer having contact segments arranged in two series of six segments electrically connected to the insulated electrodes of individual spark
- plugs, and also comprising an intermediate 40 distributer which is mounted on the rotor of the magneto and which, at each period of ignition, completes the electrical connection from the insulated terminal of said winding to a single one of said contact segments. 45
18. The combination with a four-cycle internal combustion engine having spark plugs, and a magneto having a secondary winding, of distributing mechanism comprising a rotatable main distributer having 50 two series of contact segments electrically connected to individual spark plugs, and also comprising an intermediate distributer which is electrically connected to the secondary winding, and which, at each period of 55 ignition, conducts the ignition current to a segment of one series and then to a segment of the other series, said intermediate distributor being mounted on the rotor of the magneto. 60
19. The combination with a four-cycle internal combustion engine having spark plugs, and a magneto having a secondary winding, of distributing mechanism comprising a main distributer geared to run at 65 half crank shaft speed and having two series of contact segments electrically connected to individual spark plugs, and also comprising an intermediate distributer which is electrically connected to the secondary winding 70 and which, in each two rotations of the crank shaft of the engine, conducts the ignition current to each of said contact segments in turn, said intermediate distributer being mounted on the rotor of the magneto. 75

In testimony whereof I affix my signature.

WOLFGANG E. SCHWARZMANN.
